UNITED STATES PATENT OFFICE.

ISAAC W. ENGLAND, OF PASSAIC, NEW JERSEY, ASSIGNOR TO PASSAIC METAL WARE COMPANY, OF PASSAIC, NEW JERSEY, A CORPORATION OF NEW JERSEY.

FRAME OR EASEL.

1,077,130.

Specification of Letters Patent.

Patented Oct. 28, 1913.

Application filed August 24, 1912. Serial No. 716,847.

To all whom it may concern:

Be it known that I, ISAAC W. ENGLAND, a citizen of the United States, and resident of Passaic, in the county of Passaic and State of New Jersey, have invented certain new and useful Improvements in Frames or Easels, of which the following is a specification.

My invention relates to improvements in frames, easels or the like, provided with a foldable supporting piece at the back, whereby the device may be set in an inclined position, and the parts may be snugly folded together when not in use.

The object of my invention is to provide simple and efficient means for connecting the support or leg and its brace with the frame or easel, whereby the parts may be readily applied and removed without injury.

In carrying out my invention I provide a body portion, such as a frame or plate and a back to be attached thereto, with a fastening piece that is provided with a projecting loop passing through the back, a support or leg having an opening to receive said loop, and a locking member adapted to slide through said loop, between the latter and the support, for retaining said parts securely together. Similar means may be utilized to connect to the back a brace for said support or leg, means being provided to permit relative movement between the support and brace to enable the support to be held outwardly to keep the device resting in an inclined position, or to permit the parts to be folded when not in use.

My invention also comprises novel details of improvement and combinations of parts that will be more fully hereinafter set forth and then pointed out in the claims.

Reference is to be had to the accompanying drawings forming part hereof, wherein,

Figure 1 is a rear view, partly broken, of a frame or easel embodying my invention; Fig. 2 is a vertical section thereof; Fig. 3 is an enlarged detail perspective view of the fastening piece; Fig. 4 is a section on the line 4, 4, in Fig. 3.

Similar numerals of reference indicate corresponding parts in the several views.

The body portion illustrated comprises a suitable frame or plate 1, adapted in any usual manner to serve for carrying or supporting pictures or the like, and at 2 is a

back of any suitable material to be secured to frame or plate 1 in any suitable manner. I have shown the marginal portion 1^a of frame or plate 1 as bent over the edges of back 2 to retain the latter in place.

At 3 is a fastening piece, which may be of suitable relatively thin metal, placed between frame or plate 1 and back 2, and shown provided with a loop 3^a raised a suitable distance from piece 3, which loop projects through a slot or opening 2^a in back 2.

At 4 is a support or leg, which may be of any suitable material, the upper portion 4^a of which is located against back 2 and is provided with a slot 4^b through which loop 3^a passes when said slot alines with opening 2^a of back 2, and at 5 is a retaining or locking member to pass through loop 3^a against part 4^a of support 4. Member 5 is shown provided with projections or wings 5^a to limit the sliding movement of said member through loop 3^a, the parts 5^a being adapted to bear against the loop. Member 5 may be provided with an eye 5^b, whereby the device may be hung or suspended from any suitable support. When the parts are in the position shown the support or leg 4 will be securely yet detachably connected with the body portion, and the parts may be readily detached and replaced. Support 4 is adapted to swing or hinge at 4^c so as to be moved outwardly as in Fig. 2, to retain the device in the manner of an easel.

At 6 is a brace for support 4, the lower end 6^a of which brace is provided with a slot 6^b (corresponding to the slot 4^b of support 4), and the back 2 has a slot 2^c through which slots a loop 3^a of a fastening piece 3 passes, in the manner before described with respect to support 4, the lower member 5 being passed through loop 3^a, and over the adjacent part of brace 6, to retain brace 6 upon back 2 in manner similar to that described with respect to the upper member 5^a and support 4, the lower member 5 having projections 5^a retaining said member in position. Brace 6 is adapted to be bent or swing at 6^c adjacent to back 2 and at 6^b adjacent to support 4, the end portion 6^e of which brace is shown located against the inner side of support 4. Support 4 is shown provided with a vertical slot 4^b, to which the end portion 6^e of brace 6 is slidably connected, as by an eyelet or keeper 7.

By means of my improvements support 4 and brace 6 may be readily attached to and detached from back 2, and a firm and secure attachment of the parts is effected. My improvements will be found particularly useful where the back 2 is made of cardboard or the like, and where the support 4 and brace 6 are made of similar material, since the parts are reliably held snugly together, without danger of becoming loosened, and without danger of breaking the parts when adjustments are being made.

Having now described my invention what I claim is:—

15 1. A device of the character described comprising a body portion provided with a slot, a loop passing through said slot, a support having a slot receiving said loop, and a member slidably fitted within said loop 20 against said support retaining said support upon the body portion.

2. A device of the character described comprising a body portion provided with a slot, a loop passing through said slot, a support having a slot receiving said loop, a member fitted within said loop retaining said support upon the body portion, said body portion having another slot, a loop passing through said slot, a brace having a slot receiving said loop, a member passing through said loop retaining said brace upon said body portion, and means movably connecting said brace with said support.

3. A device of the character described comprising a frame, a back secured thereto and having a slot, a fastening piece on the side of said back toward said frame and having a loop passing through said slot, a support having a slot receiving said loop, 40 and a member passing through said loop between the latter and said support retaining said support upon said back said sup-

port having a hinge portion below said member.

4. A device of the character described comprising a frame, a back secured thereto and having a slot, a fastening piece on one side of said back and having a loop passing through said slot, a brace having a slot receiving said loop, a member passing through said loop retaining said brace upon said back, a support connected with the frame and means movably connecting said brace with said support.

5. A device of the character described comprising a frame, a back secured thereto and having a slot, a fastening piece on one side of said back and having a loop passing through said slot, a support having a slot receiving said loop, a member passing through said loop retaining said support upon said back, a brace movably connected with said support, said brace having a slot, a loop passing through said slot and carried by said back, and a member passing through said loop retaining said brace upon said support.

6. A device of the character described comprising a body portion provided with a slot, a loop passing through said slot, a support having a slot receiving said loop, and a member fitted within said loop retaining said support upon the body portion, said member having an eye above said loop, and means to prevent said member from being pulled through said loop in an upward direction.

Signed at Passaic in the county of Passaic and State of New Jersey this twenty-second day of August, A. D. 1912.

ISAAC W. ENGLAND.
